MOCCASIN

Myer S. Silver, Brookline, Mass.

Application November 26, 1954, Serial No. 33,253

Term of patent 14 years

(Cl. D7—7)

Fig. 1.

Fig. 2.

Fig. 3.

Figures 2 and 3 are side and front elevational views, respectively, of the same.

The dominant features of the design reside in the element shown in full lines.

I claim:

The ornamental design for a moccasin, as shown and described.
